UNITED STATES PATENT OFFICE.

ARTHUR B. DEWES, OF ST. LOUIS, MISSOURI.

BOWLING GAME.

Application filed December 18, 1925. Serial No. 78,193.

This invention relates generally to a game apparatus and particularly to a game apparatus intended for use on a comparatively level lawn or other piece of ground, or in a 5 large room where a playing field of considerable dimensions may be marked off, the game being intended to afford amusement and healthful exercise to the players as well as to tax their skill and judgment in their 10 efforts to defeat their opponents.

Briefly stated the game apparatus disclosed herein comprises means for marking off a playing field of considerable dimensions and a plurality of members which are rolled 15 along the playing field toward a target at the opposite end of said playing field. The object of the game is for the players to score points by rolling their members to positions where said members are closer to the target 20 than are the members rolled by their opponents and the game is won by the first player or players who attain a predetermined number of points, or who shall score the highest number of points in a predetermined 25 number of innings, as the case may be.

Fig. I illustrates a side elevation of one of the targets of my improved game apparatus.

Fig. II is an end elevation of the target 30 illustrated in Fig. I.

Fig. III illustrates a playing field as it will appear when marked off on a lawn.

Fig. IV illustrates a playing field whereon a target has been arranged.

Fig. V is a view of a playing field after 35 one of the players has rolled his members toward the target.

Fig. VI is a view of a playing field after the opponent of the first mentioned player 40 has rolled his members toward the target.

In the drawing A designates a playing field which may be provided, when the game is to be played on the ground, by driving pegs B in the ground in such position that 45 when a cord C is stretched around said pegs from one to the other thereof a rectangular space within the cord will be marked off. This space constitutes the playing field and the cord C is arranged close enough to the 50 ground so that the members rolled during the game may roll over same. The pegs B are so located that the playing field is approximately five feet wide by twenty feet long.

55 D designates one of the targets forming

a part of my improved game apparatus. The targets D are preferably approximately elliptical in shape except that the ends thereof are flat as shown in Figs. I and II and said targets may be made of any suitable 60 material, for instance, wood, rubber or celluloid.

E designates members which are adapted to be rolled by one of the players toward the target D at the opposite end of the field, 65 and F designates the members adapted to be rolled by the first mentioned player's opponent. The members E are of one color and the members F are of a different color so that the members of the opposing players 70 may be distinguished from each other. Each individual member E and F is made of wood or any other suitable material and is preferably approximately elliptical in shape except that the ends thereof are flat. In other 75 words the members E and F each have approximately the same shape as the targets D but may be distinguished from said targets because said targets are distinctively colored and also because said targets may be some- 80 what larger than said members E and F.

It is apparent that because of the shape of the members E and F that it would be exceedingly difficult for the players to control the movement thereof and this adds much to 85 the enjoyment of the game for it is plain that if the members E and F had a different shape, round for instance, it would be possible for a skillful player to control the members to such extent that the game would 90 be rather uninteresting. However, by employing the elliptical members E and F, I introduce an element of luck into the game which makes it possible for a novice to cope with an experienced player and defeat him 95 if luck is with the novice.

I will now describe the manner of playing my improved game and will mention some of the rules which regulate the playing thereof.

Assume that the game is being played by four players who are paired off as partners. One player and one of his opponents take 105 positions at one end of the playing field and the first mentioned player's partner and the other opponent take positions at the opposite end of the playing field. It being previously decided which player shall roll first, the partner of said player at the opposite end of the playing field places one of the 110

- targets D in place on said playing field as shown in Fig. IV, the rules requiring that said target be placed not less than two feet from the adjacent end of the playing field.
- 5 The player who was designated to roll first then rolls his elliptical members which may be the members E for instance, toward the target D and attempts to cause said elliptical members to come to rest as close as possible to the target, as shown in Fig. V. It is then the turn of the opposing player at the end of the playing field from which the first mentioned player played, and this player rolls his elliptical members, the members F for instance, toward the target D and attempts to cause them to come to rest closer to the target than the elliptical members of the player who played first as shown in Fig. VI. Each player rolls four elliptical members and a point is scored for each elliptical member of a player which is closer to the target than all of his opponent's elliptical members. After the opposing players at one end of the playing field have rolled the elliptical members as described, the player who was the winner will place the second target on the playing field at his end thereof and the players at the opposite end of said playing field will roll the elliptical members toward said target as already described, the partner of the player who scored the point or points when play was from the opposite end of the field being the first to roll.
- 35 The targets D are capable of moving about the playing field and it is permissible for a player to strike the target with one of his elliptical members and thus drive it away from his opponent's elliptical members.
- 40 which may be rather close to the target, thereby giving the player rolling a better opportunity to roll his elliptical members close to the target. The rules of play call for a player being penalized if desired for
- 45 every one of his elliptical members which rolls off the playing field, this being designated as "out of bounds" or "a foul". Also a penalty may be exacted if a player strikes a target and drives it off of the playing field, and in this event the target is replaced on the playing field at the transverse center of the field and two feet from the end

of the playing field toward which play is being directed.

The predominant feature of the present invention and the point that differentiates the game from similar games is found in connection with the shape of the members E and F and the shape of the targets D, for it is apparent that because of the shape of the members E and F it would be very difficult to control same while they are being rolled and also because of the shape of the target the striking of said target may result in irregular movement being imparted thereto, which could not easily be calculated before hand.

It is obvious that the game disclosed herein may be played in accordance with various rules and by players of various numbers. For instance two, four, or a greater number of players may play a game, and eleven or twentyone or any other number of points may be designated as "out". Also the winner or winners may be determined by the player or players who have the greater number of points in a predetermined number of innings, or turns at the opposite ends of the field, and progressive games may be played by eliminating the losers from the game and matching the winners until the ultimate winner is decided in the final match.

It is plain that I may give to the targets some shape other than the one they have in the drawing, for instance, said targets may be made round. When the game is played indoors, some means other than the pegs B will be employed to hold the cord C but it is obvious that many substitutes for the pegs may be used.

I claim:

An improved article of manufacture for use in playing a game, comprising an elongated member having its opposite ends uniformly tapered and terminating in flat surfaces, the cross-sectional shape of said member in a direction parallel to the longitudinal axis thereof being elliptical, and in a direction transverse to the longitudinal axis thereof being circular, said member being of a substantially uniform density throughout.

In testimony that I claim the foregoing I hereunto affix my signature.

ARTHUR B. DEWES.
